UNITED STATES PATENT OFFICE.

HENRY A. HAYDEN, OF JERSEY CITY, NEW JERSEY.

DUSTER.

No. 823,725.

Specification of Letters Patent.

Patented June 19, 1906.

Application filed September 9, 1905. Serial No. 277,661.

To all whom it may concern:

Be it known that I, HENRY A. HAYDEN, a citizen of the United States, residing in Jersey City, in the county of Hudson and State 5 of New Jersey, have invented certain new and useful Improvements in Dusters, of which the following is a specification.

This invention relates to the class of dusting devices suitable for moving dust from furniture, base-boards, and the like; and it has for its object to provide a device for this purpose composed in part of felt and in part of fiber, which will act the part of a wiper and take up the dust and will enable the 15 user to get at and clean parts that are difficult of access.

In the accompanying drawings, which serve to illustrate an embodiment of the invention, Figure 1 is a perspective view of the 20 duster. Fig. 2 is a longitudinal section of same, showing the construction. Fig. 3 is a cross-section on a scale larger than that of the principal views.

The drawings illustrate the duster in its 25 preferred form.

A is the handle, on the extreme end of which is fixed a tuft of fiber B, which forms a brush. On a flattened portion a of the handle is a flattened body C, forming the main 30 cleaner and wiper of somewhat peculiar construction. This body portion will be of felt, preferably combined, however, with fiber, as will be explained.

In constructing the body part C of the device two sheets c c, of thick felt slitted at their lateral edges and having a general oblong rectangular form, embrace the flattened portion a of the handle and at the respective sides of the handle between their slitted 40 margins are disposed two folded and slitted strips of felt d. These parts c and d are secured together by stitching e. In addition to the folded strips d it is preferred to embrace between the plies of each folded strip a layer of fiber f, which will be secured in place 45 by the stitching. The handle may be fur-

ther secured in place between the sheets c by means of stitches g, in which the thread passes through holes bored in the handle. The slitted felt removes and wipes up the 50 dust, and the brush B is useful in removing dust from angles and other places difficult of access. The fiber referred to as forming the brush B and the layer f may be the long vegetable fiber used for cheap brushes, of which 55 coir is a type; but hair might be employed and is intended to be included under the word "fiber." The fiber f at the lateral edges of the body is preferred; but the present invention is not restricted to its use.

Having thus described my invention, I claim—

1. A duster, having a handle, a fiber brush at the end of the handle, and a body composed of plies of felt embracing the handle 65 and slitted at their lateral edges.

2. A duster, having a handle, a brush secured to the end of the handle with its fibers extending substantially parallel with the handle, and a body consisting of two sheets 70 or plies of felt which embrace the handle and are slitted at their lateral margins, and pieces of slitted felt between said plies at the respective sides of the handle, the felt being secured together at the sides of the handle.

3. A duster, having a handle A, with a flattened portion a, a brush B on its end composed of fiber, and a body portion C, composed of two sheets c, c, of thick felt, embracing the flattened handle and slitted at 80 their lateral edges, the folded and slitted pieces of felt d embraced between the sheets c, c at the respective sides of the handle, and the fiber f between the folds of the felt d, as set forth.

In witness whereof I have hereunto signed my name, this 8th day of September, 1905, in the presence of two subscribing witnesses.

HENRY A. HAYDEN.
